UNITED STATES PATENT OFFICE.

MAX H. BAKER, OF OSHKOSH, WISCONSIN.

LOOSE-LEAF BINDER.

1,040,992.

Specification of Letters Patent. Patented Oct. 15, 1912.

Application filed March 7, 1912. Serial No. 682,197.

To all whom it may concern:

Be it known that I, MAX H. BAKER, a citizen of the United States, residing at Oshkosh, in the county of Winnebago and State 5 of Wisconsin, have invented certain new and useful Improvements in Loose-Leaf Binders; and I do declare the following to be a full, clear, and exact description of the invention, such as will enable others skilled 10 in the art to which it appertains to make and use the same.

This invention relates to improvements in loose leaf book covers or binders and is designed as an improvement over the 15 binder shown in my Patent #906,365, dated December 8, 1908:

The object of the invention is to provide a binder or cover of this character having means for permitting the removal from the 20 book of the loose leaves without unlacing the binding cord.

With these and other objects in view the invention consists of certain novel features of construction, combination, and arrangement of parts as will be more fully described hereinafter and claimed.

In the accompanying drawings; Figure 1 represents a plan view of the front face of a book equipped with this invention; Fig. 10 2 is a view of the rear face of the book; Fig. 3 is a plan view of the inside of a book opened out flat; Fig. 4 is a longitudinal section taken on line 4—4 of Fig. 1; Fig. 5 is a plan view of the outer side of the 25 cover showing the manner in which the binding cord is released to permit the cover sections to be opened out flat; Fig. 6 is a transverse section of the book with the 30 covers opened back to back for use on the 40 arm of a chair.

In the embodiment of the invention front and back cover sections 1 and 2 are provided each of which consists of a main or body portion 3 and a hinge strip 4. These parts 45 may be made of paper board or any suitable material and the body portion 3 is preferably connected to the hinge strip 4 by the fabric covering of the boards, said covering being applied to the body portion and 50 hinge strip in one piece as shown.

In each hinge strip 4 of each cover section is arranged a series of eyelets 5 so when the cover sections are in proper position on the leaves of the book they will be in alinement, and a binding cord 6 is adapted to be passed through said alined eyelets. The bind-

ing cord has formed therein near one end a knot 6² and in applying the cord to the cover sections the longer end of the cord is passed through the registering eyelets at 60 one end and then through the registering eyelets at the other end and this end of the cord is provided with a fastening device preferably in the form of a resilient socket 7 which is adapted to engage with a stud 8 secured to the outer face of the hinge strip of one of the cover sections preferably at a point about midway of the length of said strip, when this end of the cord is drawn through the eyelets far enough to allow the 65 socket 7 to be engaged with the stud 8.

When it is desired to open the book out flat the socket 7 is disengaged from the stud 8 which will permit the cord to be drawn through the eyelets thus permitting slack 70 in the loop formed between the eyelets which will permit the cover sections to be drawn apart a greater or less distance according to the length of the loop and the length of the cord whereby the cover sections may be laid 75 flat and the leaves opened out thereon. This arrangement greatly facilitates the use of the book for many purposes and enables a ruler to be laid flat across the pages. In constructing the cover or binder the cord 80 should be of sufficient length to permit the loop between its ends to be loosened when desired to accommodate additional leaves which may from time to time be added to the book and by tying a loop at the other 85 end of the cord the same may be readily released when desired such for instance as in the substitution of a new cord.

The cover above described is the same as that shown in the patent above referred to 90 and it will be obvious that when this construction is employed it is necessary to thread the binding cord through apertures formed in the rear edge of the leaves to be bound, and to remove one of said leaves or 95 to insert a new one necessitates the unlacing and relacing of the binding cord, at least the releasing of the ends thereof and the removal of one of the covers. It is to obviate these objectionable features that this 100 invention is designed and which consists in providing one of the hinge members 4 on its inner face with a plurality of longitudinally spaced laterally projecting studs 10 105 two being here shown arranged between the apertures formed in the hinge member to which they are applied. These studs are de-

signed to be passed through apertures 11 formed in the rear edges of the leaves 12 to be bound as shown clearly in Fig. 1, said apertures being formed by a suitable punch. 5 These leaves 12 are also provided at their rear edges at points registering with the cord apertures in the hinge members with apertures 13 which open through the rear edges of the leaves to provide for the sliding of 10 the leaves from the binding cord at opposite ends of the binder as shown clearly in Fig. 1.

When it is desired to place a new leaf 12 on the binder all that is necessary is to release the socket 7 from the stud 8 and 15 open the binder into flat position shown in Fig. 1 when a leaf 12 having apertures 11 and 13 described above therein may be engaged with the studs 10 and the binding cord in the manner described.

20 The other hinge member 4 of the other cover is provided with a plurality of apertures 14 arranged to register with the studs 10 on the hinge member of the co-operating cover and said studs are adapted 25 to pass through said apertures 14 when the covers are in closed binding position. It will thus be seen that a leaf may be applied to or removed from the book without interfering with the lacing cord.

30 I claim as my invention:

1. A loose leaf binder comprising front and back cover sections having near their rear edges a series of alined eyelets or apertures, a flexible binding element laced 35 through said eyelets and fastened at one end, means for fastening the free end of said binding element when said element is drawn tight, studs extending laterally from the inner face of one of said cover sections 40 the other section having eyelets arranged near its rear edge in position to register

with the studs of the first mentioned section and adapted to be engaged therewith.

2. A loose leaf binder comprising front and back cover sections having near their rear edges a series of alined eyelets or apertures, a flexible binding element laced through said eyelets and fastened at one end, means for fastening the free end of said binding element when said element is drawn tight, studs extending laterally from the inner face of one of said cover sections the other section having eyelets arranged near its rear edge in position to register with the studs of the first mentioned section and 55 adapted to be engaged therewith, and removable leaves for insertion between said covers having a plurality of apertures arranged near one edge in position to fit over the studs of one of the cover sections and 60 open slots disposed to register with the eyelets through which the binding element passes.

3. The combination with a loose leaf binder comprising front and rear sections 65 having a series of alined eyelets near their rear edges, a flexible binding element laced through said eyelets, one of said sections having laterally extending longitudinally 70 spaced studs of detachable leaves having apertures positioned to register with the studs of the cover section and slots opening through the rear edge thereof positioned to register with the eyelet through which the binding element passes. 75

In testimony whereof I have hereunto set my hand in presence of two subscribing witnesses.

MAX H. BAKER.
